FRONT OPENING WATCH BOX

Francis E. Blod, Tuckahoe, N. Y., and Alfred M. Blumenfeld, Hackensack, N. J., assignors to The Gruen Watch Company, Cincinnati, Ohio, a corporation of Ohio

Application September 21, 1950, Serial No. 12,282

Term of patent 14 years

(Cl. D80—5)

To all whom it may concern:

Be it known that we, Francis E. Blod and Alfred M. Blumenfeld, both citizen of the United States, and residing at Westchester County at Tuckahoe, New York, and Bergen County at Hackensack, New Jersey, respectively, have invented a new, original, and ornamental Design for a Front Opening Watch Box, of which the following is a specification, reference being had to the accompanying drawing, forming a part thereof.

Figure 1 is a side elevational view of the front opening watch box, showing our new design.

Figure 2 is a front elevational view thereof.

Figure 3 is a side elevational view of the watch box shown in open position.

Figure 4 is a front elevational view of the watch box in open position.

Figure 5 is a top plan view thereof showing the watch box in closed position.

We claim:

The ornamental design for a front opening watch box, substantially as shown.

FRANCIS E. BLOD.
ALFRED M. BLUMENFELD.
